UNITED STATES PATENT OFFICE.

PAUL T. MITTAG, OF LOS ANGELES, CALIFORNIA.

EXERCISING COT.

Application filed April 12, 1928. Serial No. 101,440.

This invention relates to exercising apparatus, and more particularly to an exercising cot, and the general object of the invention is to provide an exercising cot on which a person, in a reclining position, may effectively exercise his arms, legs, body and neck.

Other objects and advantages will appear hereinafter.

In this specification and the annexed drawings I disclose my invention in the form which I consider the best, but I do not limit my invention to such form because it may be embodied in other forms, and it is to be understood that in and by the claims of this specification I intend to cover my invention in whatever form it may be embodied.

In the drawings:

Fig. 1 is a side elevation of my exercising cot, showing a man reclining thereon with his head raised, his back lowered and his legs retracted, the head rest, back engaging strap and foot rest of the cot being respectively raised, lowered and retracted to support the occupant in such position.

Fig. 2 is a side elevation of the cot showing the head rest, back engaging strap and foot rest respectively lowered, raised and extended, whereby the occupant's head is lowered, his back raised and his legs extended.

Fig. 3 is a side elevation of one of the auxiliary frames and the operating means mounted thereon.

Fig. 4 is a front elevation of the auxiliary frame and operating means shown in Fig. 3.

Fig. 5 is a perspective view of the cot frame with certain parts shown thereon and other parts left off.

Fig. 6 is a transverse vertical section taken on line 6—6 of Fig. 5 of one of the frame section locks.

Fig. 7 is a side view of one of the head rest strap roller guide means.

Fig. 8 is a front view of said guide means shown in Fig. 7.

Fig. 9 is a perspective view of one of the connecting means for the back engaging strap and one of the straps to which the former strap is connected.

Corresponding reference characters designate the same parts in all the figures.

Referring in detail to the drawings 1 designates a rectangular frame made in two U-

shaped sections 2 and 3. The sections 2 and 3 are made of metal tubing, the section 2 being bent at two points at right angles to form an end member 4 and a pair of side members 5, and the section 3 being bent at right angles at two points to form an end member 6 and a pair of side members 7. The tubing of which the section 2 is formed is slightly larger in diameter than the tubing of which the section 3 is formed, so that the side members 7 of section 3 may fit and telescope within the side members 5 of the section 2. The end member 6 of section 2 is bowed downwardly for the purpose hereinafter described. The frame 1 is supported on three pairs of legs 8, 9 and 10, the legs 8 and 9 supporting the frame section 2 and the legs 10 supporting the frame section 3. The legs 8 extend vertically and are secured at their upper ends to the frame section 2 at the junctures of end member 4 and side members 5 respectively. The legs 9 are secured at their upper ends to the side frame members 5 of section 2 about two thirds the length of said section from the legs 8. The legs 10 are secured at their upper ends to the frame section 3 at the juncture of the side members 7 and the end member 6 of said section.

A head rest 11 is pivotally mounted in the outer or head end of the frame section 2. The upper, lower and outer sides of said head rest are rectangular, and the head rest is triangular in cross section, the lower and upper sides of the rest converging inwardly from said outer side to the inner side edge of the rest, at which edge the rest is pivoted to the inside of the side members 5 of frame section 2 by pivots 12 projecting from the ends of the rest into bearings 13 on the side members 5, so that the rest may swing up or down from said inner edge within the outer end of said frame section 2. An inverted U-shaped supporting frame 14 for the head rest 11 is pivoted at the lower ends of its side arms to the legs 8 at 14', and a link 15 is connected at one end to one of said side arms and at its other end to a lever 16, which is pivoted to one of the side members 5 of the frame section 2 rearwardly of the head rest 11, which lever may be grasped by the occupant of the cot and swung rearwardly to swing the frame 14 through link 15 under the outer side of the head rest 11 to support said side of the rest in raised position.

Upstanding auxiliary frames 17 are clamped on the side members 5 respectively of the frame section 2, there being a pair of clamps 18 on each auxiliary frame for clamping said side members in the front and in the rear of the legs 9. Yokes 19 are formed on the upper part of the auxiliary frames 17 in which are respectively journaled drums 20, each of which drums is divided into two sections 21 and 22. To the drum sections 21 are secured one end of straps 23, and to the drum sections 22 are secured one end of straps 24. On the lower forward portion of the auxiliary frame 17 are journaled rollers 25 under which the straps 23 extend. Rollers 26 and 27 are journaled in clamps 28 which are clamped on the end frame member 4 adjacent the legs 8 respectively, the rollers 27 being journaled above the rollers 26 and above said end member 4. The straps 23 extend from the rollers 25 under the rollers 26 and over the rollers 27 and are secured at their outer ends to the under side of the head rest 11 at the lower outer corners thereof. Rollers 29 are journaled on the inside of the lower forward part of the auxiliary frames 17 parallel to the drums 20, and rollers 30 are journaled on the inside of said frames above and at right angles to the rollers 29 and parallel to the side members 5 of frame section 2. The straps 24 extend from the drum sections 22 under the rollers 29 and upwardly from said rollers, with a quarter twist, over the rollers 30 and downwardly from said latter rollers to the ends of a back engaging strap 31 which extends transversely of the frame section 2, the ends of the back engaging strap being connected by connecting plates 32 to the adjoining ends of the straps 24 respectively, said plates being provided with slots 33 and 34 through which the ends of the straps 31 and 24 are respectively extended and doubled back upon said straps and secured respectively thereto. Crank shafts 35 are journaled in the upper ends of yokes 19 and cranks 36 and pinions 37 are secured on said shafts, which pinions mesh with gears 38 on the journals 39 of drums 20.

A sheet of canvas 40 is secured at its side edges to the side members 5 of frame section 2 and extends from the rear edge of the head rest 11 over the back engaging strap 31 to the rear end of said side members and section, which sheet supports the body of the occupant of the cot.

In the upper side and near the rear ends of the side members 5 of the frame section 2 are provided apertures 41. Frame section locks 42 are mounted on clamps 43 which are clamped on the side members 5 over the apertures 41. Brackets 44 are secured on the upper side of the clamps 43. The locks 42 comprise locking bolts 45, cams 46 and springs 47. The bolts 45 are slidably mount-

ed in the brackets 44 and apertures 43' of clamps 43 and the cams 46 are pivoted to the upper ends of said bolts above said brackets, while the springs 47 surround the bolts 45 between the upper wall of the brackets and an external flange 48 on the bolt. Handles 49 may be formed on the cams 46 for operating the same. The side members 7 of the frame section 3 are provided in their upper walls with a plurality of longitudinally spaced apertures 50 adapted, respectively, to register with the apertures 41 in the side members 5 of frame section 2, to receive the lower end of the locking bolt 45, whereby the frame sections 2 and 3 may be locked together with the outer end of section 3 adjacent the ends of the side members 5 of section 2, or said outer end extended to different lengths from the ends of said side members, thus locking the frame 1 in different lengths. The springs 47 normally hold the lower ends of the bolts 45 in apertures 50 of the side members 7 of frame section 3, while the cams 46 are turned down as shown in Figs. 5 and 6. By turning the cams 46 up and into engagement with the brackets 44 the bolts 45 are withdrawn from the apertures 50 and the frame sections 2 and 3 unlocked so that they may be adjusted as to length by telescoping the side members 7 within the side members 5 or withdrawing the former side members from the latter.

A slideable foot rest 51 is slidably mounted on the outer end of the frame section 3, which rest comprises a transverse foot angle bar 52 and a pair of rods 53 screw seated at their outer ends in the ends respectively of said angle bar, which rods extend at right angles from said bar through apertures 54 in the outer wall of end member 6 of frame section 3 into the side members 7 of said section. Springs 55 surround the rods 53 within the side members 7 of frame section 3 and bear at their rear ends against the rear wall of the end member 6 of said section. Heads 56 are screw seated on the inner ends of the rods 53 against the inner ends of the springs 55 so that said springs will normally hold the foot rest 51 retracted against the end member 6 of frame section 2. Lock nuts 59 are screwed on the inner ends of the rods 53 against the heads 56 to lock said heads against turning off the rods.

Stirrups 60 are secured on the inner side of the foot bar 52 in which the occupant of the cot places his feet.

The operation of my invention is as follows: The occupant of the cot lies on his back upon the sheet 40 with the back of his head upon the head rest 11, his feet in the stirrups 60 and his hands grasping the cranks 36, the bowing of the end member 6 downwardly accommodating the occupant's legs and feet so that his feet may rest properly in said stirrups. Upon turn-

ing the cranks 36 in one direction the straps 23 are unwound from the drum section 21 and the head rest and the occupant's head allowed to swing down by gravity on the 5 pivots 12, while the straps 24 are wound on the drum sections 22 and the back engaging strap 31 drawn upwardly against the sheet 40 and the small of the occupant's back, whereby the occupant's body is bent 10 upwardly at the small of his back. Upon reversing said cranks the head rest and the occupant's head are raised while the belt 31 and the occupant's body at the small of his back are lowered. While raising and 15 lowering his head and body the occupant may also exercise his legs by alternately pushing the foot rest 51 rearwardly by his feet in the stirrups 60 against the tension of springs 55, and then allowing the springs 20 to retract the foot rest and the occupant's legs.

What I claim is:

1. An exercising cot, a frame, a body rest on said frame, a head rest on said frame, 25 a back engaging member mounted on said frame to be raised and lowered and to engage the occupant under the small of the back, and means for raising and lowering said back engaging member for raising and 30 lowering the occupant's body at the small of his back.

2. In an exercising cot, a frame, a body rest on said frame, a head rest on said frame, a back engaging member mounted on said 35 frame to be raised and lowered and to engage the occupant under the small of the back, and means operable by the occupant of the cot for raising and lowering said back engaging member for raising and lowering the occupant's body at the small of 40 his back.

3. In an exercising cot, a frame, a body rest on said frame, a head rest pivoted on said frame, a back engaging member mounted 45 on said frame to be raised and lowered and to engage the occupant under the small of the back, means for swinging said head rest up and down and means for raising and lowering said back engaging means.

50 4. In an exercising cot, a frame, a body rest on said frame, a head rest on said frame, a back engaging member mounted on said

frame to be raised and lowered and to engage the occupant under the small of the back, means operable by the occupant of the 55 cot for swinging said head rest up and down, and means operable by the occupant for raising and lowering said back engaging means.

5. In an exercising cot, a frame, a body rest on said frame, a head rest on said frame, 60 a back engaging member mounted on said frame to be raised and lowered and to engage the occupant under the small of the back, means for swinging said head rest up and down, means for raising and lowering 65 said back engaging member under the occupant's back, and an exercising foot rest on said frame to be operated by the feet of the occupant.

6. In an exercising cot, a frame, a head 70 rest pivoted on said frame, a drum, a strap connected at one end to said drum and at its other end to said head rest, and a crank to be grasped by the occupant of the cot for 75 rotating said drum to wind said strap thereon and to unwind said strap therefrom to raise and lower said head rest.

7. In an exercising cot, a frame, a body rest on said frame, a back engaging strap, two drum straps connected at one end to 80 said drums, respectively, and at their other ends to said back engaging strap, and cranks to be grasped by the occupant of the cot for 85 rotating said drums to wind said straps thereon or to unwind said straps therefrom to raise and lower said back engaging strap under the occupant's back.

8. In an exercising cot, a frame, a head rest pivoted to said frame, a back engaging strap, a pair of drums, each of said drums 90 being divided into two sections, two straps connected at one end to one of the sections of said drums respectively, and at their other ends to said head rest, two other straps connected at one end to the other sections of 95 said drums respectively, and at their other ends to the ends respectively of said back engaging strap, and cranks arranged to be operated by the occupant of the cot to rotate said drums to wind said straps on said drum sections and to unwind said straps from 100 said drum sections to raise and lower said head rest and said back-engaging strap.

PAUL T. MITTAG.
